HYDROGENATING GAS GENERATING APPARATUS

Milon J. Trumble, Alhambra, and William L. Seeley, Los Angeles, Calif., assignors to Processco, Limited, San Francisco, Calif., a corporation of Nevada

Application December 13, 1930
Serial No. 502,144

5 Claims. (Cl. 48—75)

This invention relates to the hydrogenation of petroleum oils in the production of lighter fractions and refers particularly to one of the apparatus units in a continuous process of hydrogenation.

The objects of the invention are to provide apparatus which will continuously separate the lighter oil from carbonaceous matter in sludge oil for continuous return to a cyclic hydrogenation system of which the present apparatus is a part, while continually treating the carbonaceous matter with superheated steam at high temperature for dissociation into gases for recycling with the oil.

Other objects of the invention will appear in the following description and accompanying drawing.

In the drawing Fig. 1 is a vertical section of the apparatus.

Fig. 2 is a cross section of Fig. 1 taken along the line 2—2 of Fig. 1.

In further detail the apparatus comprises a vertical steel cylinder F flanged at its lower end at 2 and bolted to a heavy steel base 3 the interior of which base is bowl-shaped and provided with a steam inlet passage or pipe 4 fitted with an upwardly directed distributing nozzle 5 spaced above which is an inverted bowl-shaped perforated bridge 6 preferably of refractory material.

Above the bridge piece 6 and extending across the cylinder at spaced intervals are circular metal screens 7 each resting on its edge on angle irons 13 secured to the wall of the cylinder and each provided with a central aperture surrounded by a circular wall 7' projecting both above and below the screen, while at the side of the cylinder is a removable door or plate 10 through which the screens are accessible either for removal or for the renewal of layers of catalytic material thereon.

Spaced above the topmost screen is a conical partition 11 welded to the cylinder and which provides a chamber above for oil 12 from hydrogenating or cracking stills to enter through a pipe 35 for settling of its heavier constituents into the lower end of the cone 11 for continual feeding of said constituents through a rotary feeder having four vanes 14 operating in a circular housing 15 bolted at 16 to the outwardly flanged lower edge of cone 11.

In cross section the rotary feeder housing 15 is square as shown in Fig. 2, though the cone 11 above it would gradually change its form to round where it meets the cylinder walls. The

feeder housing is also split or parted along its vertical center line at X to permit close machining and fitting of the feeder, the two halves of the housing being held together with bolts or rivets 17.

The lower end of feeder housing is open and provided with a steam injection passage or pipe 18 so that if the sludge 12' will not drop freely as the feeder revolves, a light continuous blast of superheated steam will cut it loose and drop it in a stream through the large central openings in screens 7 to the reaction bowl in base 3 where a constant blast of superheated steam from supply pipe 56 at about 1400° F. is maintained.

The depth of the oil 12 in the oil chamber is limited by an overflow pipe 20 which carries the overflow to a float tank 21 of any conventional design for automatically starting and feeding a pump Z² in the manner well understood and not detailed as not involving anything new. The oil from the pump is forced back through pipe 8 for recycling in the hydrogenating system mentioned.

At a relatively short distance above the oil level the cylinder is outwardly flanged and closed by a head 22 above which, and if desired held by the same marginal bolts 23, is a gas compartment 24 connected to the space in the lower compartment by a pipe 25, while within the gas compartment are horizontally arranged screens 26 spaced one above the other similar to lower screens 7 and also adapted to carry layers of catalytic material. A door 27 at the side of the gas compartment provides for removal of the screens or change of the catalytic material.

It should be noted that this door as well as lower door 10 has its wall shaped to fit in place and continue the inner wall of the cylinder F so that the gases will have to go through the screens and not around the edges.

At the top of the gas compartment is a gas outlet delivering directly to a gas distributing pipe 9, or by way of a gas pump Z³, suitable piping and valves being supplied as indicated to permit of this.

Safety and relief valves may be placed on the apparatus as respectively indicated at 28 and 29, and temperature and level gages may also be installed if desired.

To insure control of the flow of material through the feeder it is driven by a motor 30 through a variable speed transmission 31 of any desired design, the slow speed shaft 32 of which carries a worm in mesh with worm gear 33 on 110

a shaft 34 in turn carrying a bevel pinion 36 meshing with a large gear 37 on the end of the feeder shaft which projects through the side of the cylinder, suitable packing means being 5 provided to prevent gas leakage at this point. Thus the speed of the feeder and consequent stream of heavy material delivered to the lower or reaction part of the chamber may be determined with accuracy.

10 The construction of the upper or gas compartment 24, it will be noted, provides for easy removal or placing of this in position, though it is manifest that this compartment need not be directly on top as it is only a continuation 15 of the generating or reaction chamber so as to gain the advantage of further time and exposure of the gases to a catalyst.

In operation the screens are each covered with a layer of a catalytic material such as iron oxide, 20 the heavy oil from the still is constantly flowed in and out of pipes 35 and 8 respectively, the feeder is adjusted to continually drop the heavy constituents of the oil, mostly carbon, to the bottom where a blast of superheated steam at 25 about 1400° F. meets it with instant volatilization of its liquid constituents and reacting on the carbon to dissociate the steam.

The following approximate reactions occur:

Some of the H₂ reacts with C to form C_nH_{2n+2} series and other gases attendant on water gas formation.

35 (Without the use of a catalyst the approximate reaction would be, C + 2H₂O = 2H₂ + CO₂ - 32,650 B. t. u. and in which case the drop in temperature would make it preferable to restore this by applying additional heat to the chamber to avoid the 40 entering of too much steam into the system).

The composite of gases released contain some of the C₂H₄ series and C₂H₂ series (due to some residual oil in the carbon and to partial hydrogenation), CO, slight amount, free H₂ from 20 to 45 30%, also some of the lighter members of the C_nH_{2n+2} and C_nH_{n+2} series.

50 By adding a promoting agent to the iron oxide, such as 2.5% of Cr₂O₃ + 0.5% of CeO₂, the reaction will be accelerated about 700 times at a temperature around a thousand degrees F.

The continuous admission of the superheated steam at a higher temperature and pressure than that maintained in the other parts of the continuous system of which this apparatus is a part, 55 together with the expansion caused by the reactions above given yield ample pressure for forcing the produced gases back through pipe 9 for recycling through the system to effect hydrogenation, but if desired, a gas pump Z³ may be turned 60 into the line to boost the pressure or to inject additional hydrogen or other gases to the gas stream.

It is of course understood that the apparatus

is all suitably packed with heat insulation as indicated at 37, also that various modifications may be made within the spirit of the invention and scope of the appended claims.

We claim:—

1. Gas generating apparatus comprising an oil-receiving chamber provided with a conical bottom forming a settling and decanting tank, a revolvable feed control gate at the small end of said conical bottom adapted for feeding the carbonaceous sludge from the oil in a measured flow, a reaction chamber into which said sludge is fed, means for directing a blast of superheated steam upon the sludge for gasifying the same, and a pipe for taking off gas from the upper part of the reaction chamber.

2. Gas generating apparatus comprising an oil-receiving chamber provided with a conical bottom forming a settling and decanting tank, a revolvable feed control gate at the small end of said conical bottom adapted for feeding the carbonaceous sludge from the oil in a measured flow, a reaction chamber below said receiving chamber into which said sludge is fed so as to fall to the lower part thereof, means for directing a blast of superheated steam upon the sludge for gasifying the same, a screen positioned across the reaction chamber below the feed control gate adapted to hold a reaction promoting agent, and a pipe for taking off gas from the upper part of the reaction chamber.

3. Gas generating apparatus comprising a reaction chamber, means for dropping carbonaceous sludge from above into the chamber, means for directing superheated steam into the sludge 110 at the bottom of the chamber, a screen positioned across the reaction chamber through which the sludge must fall adapted to hold a reaction promoting agent, and a pipe for taking off gas from the upper part of the chamber, after passing upwardly through said screen.

4. Gas generating apparatus comprising a reaction chamber, means for dropping carbonaceous sludge from above into the chamber, means for directing superheated steam into the sludge 120 at the bottom of the chamber, a plurality of spaced screens positioned across the reaction chamber provided with a relatively large passage-way other than the screen openings through which the sludge must fall, while the gases generated rise through the screen proper.

5. Gas generating apparatus comprising a reaction chamber adapted to hold oil sludge, a feeder for carbonaceous oil sludge at the upper part of the chamber comprising a revolvable 130 pocket wheel delivering successive pockets-ful of sludge to the chamber, a steam jet directed into the pockets as they come around arranged to aid the sludge in falling from the pockets, and means directing superheated steam into the 135 sludge at the bottom of the chamber.
